UNITED STATES PATENT OFFICE.

CHRISTIAN WASHBURN, OF BRIDGEWATER, MASSACHUSETTS.

HAMMOCK-SWINGING APPARATUS.

SPECIFICATION forming part of Letters Patent No. 483,753, dated October 4, 1892.

Application filed October 9, 1891. Serial No. 408,213. (No model.)

To all whom it may concern:

Be it known that I, CHRISTIAN WASHBURN, a citizen of the United States, residing at Bridgewater, in the county of Plymouth and 5 State of Massachusetts, have invented certain new and useful Improvements in Hammock-Swinging Apparatus, of which the following, taken in connection with the accompanying drawings, is a specification.

10 The object of my invention is to produce a hammock-swinging apparatus whereby a person in the hammock can cause it to swing by a slight motion of the hand.

The invention consists of a bell-crank lever 15 pivoted to an arm that is secured to one of the posts or supports carrying the hammock, and a cord connecting the short arm of the lever and the rope of the hammock, and another cord attached to the long arm of the 20 lever, which cord is operated by the person occupying the hammock.

Referring to the accompanying drawings, Figure 1 represents a hammock supported from two posts, to one of which is attached a 25 swinging apparatus embodying my invention. Fig. 2 is a plan or top view of one end of the same, drawn to a larger scale. Fig. 3 is an isometrical perspective view of the swinging apparatus.

30 A A represent posts provided with hooks B B, to which the hammock C is hung.

D is an arm secured to one of the posts A a short distance below the hook B. To the outer end of the arm D is pivoted a bell- 35 crank lever E, to the short arm e of which is secured one end of a rope F, the other end of which is looped and passed over the hammock-rope C' before it is placed upon the hook B. To the long arm e' of the bell-crank 40 lever E is secured a long rope G, the free end of which extends toward and rests in the hammock, so as to be operated by the occupant.

In the drawings I have shown rings secured to the end of each arm of the bell-crank lever 45 for attaching the ropes; but of course they could be formed with holes and the rings be dispensed with.

As the hammock is suspended longitudinally between the supports, one at each end, 50 its movement is in the nature of a partial rotation with the points of suspension, as an

axis, and as the main portion of it when at rest is suspended from the supports the bell-crank lever must be pivoted so that its arms will move in a horizontal plane, so that when 55 the draw upon the longer cord is exerted the motion will be transmitted to the hammock to move it in a lateral direction, and as the movement or swinging of the hammock is increased the suspended portion will move in 60 the arc of a circle. The construction of applicant's device also admits of the hammock being operated in narrow halls or on verandas, where it is necessary to have the operating mechanism as compact as possible to 65 avoid being in the way, and also to avoid all undue friction as where the cord would be passed over a pulley and also to permit of this force being exerted by the short movement of the arm that can be had when a person is lying in a hammock. 70

The operation is as follows: The person occupying the hammock takes hold of the rope G and draws upon the same, which communicates motion to the bell-crank lever E, and 75 by the rope F to the hammock-rope C', and causes it to vibrate and thus impart a swinging motion to the hammock. It will be seen that a very slight movement imparted to the cord C' will cause the hammock to swing a 80 considerable distance, thus the operator has to move his hand but slightly and that in a line longitudinally of his body if he is lying down.

What I claim as my invention is— 85

The combination, with two supports, of a hammock horizontally suspended therefrom, the connection between the hammock and the supports being such that the hammock can have a lateral and vertical movement relatively to the supports, a bracket secured to one of the supports and projecting laterally therefrom relatively to the hammock, a bell-crank lever pivotally secured at its angle to the outer end of the bracket, with its arms 95 movable in a horizontal plane, one arm of the lever projecting toward the center of the hammock and the other arm projecting substantially toward the support, a cord secured to the outer end of the first-mentioned arm and 100 connecting with the hammock near the support, and another cord secured to the outer end

of the other arm and extending to the central portion of the hammock and adapted to be drawn longitudinally by the occupant, said cords crossing each other near the support, substantially as set forth. In testimony whereof I have signed my name to this specification, in the presence of

two subscribing witnesses, on this 7th day of August, A. D. 1891.

CHRISTIAN WASHBURN.

Witnesses: JOSEPH TOOKER, LORIN HEITH.
